UNITED STATES PATENT OFFICE.

GEORGE W. JOHNSTON, OF ST. JOSEPH, MISSOURI.

AIR OR LIQUID RECIPROCATING PUMP HAVING ROTARY OPERATING MECHANISM.

SPECIFICATION forming part of Letters Patent No. 717,750, dated January 6, 1903.

Application filed January 9, 1902. Serial No. 89,027. (No model.)

To all whom it may concern:

Be it known that I, GEORGE W. JOHNSTON, a citizen of the United States, residing at St. Joseph, in the county of Buchanan and State 5 of Missouri, have invented certain new and useful Improvements in Air or Liquid Reciprocating Pumps Having Rotary Operating Mechanism; and I do declare the following to be a full, clear, and exact description of the 10 invention, such as will enable others skilled in the art to which it appertains to make and use the same, reference being had to the accompanying drawings, and to the letters of reference marked thereon, which form a part 15 of this specification.

My invention relates to improvements in reciprocating pumps having a rotary operating mechanism adapted to pump air, water, or any liquids or gases and which are especially adapted to assist in propelling vehicles 20 that run by air by attaching the pumps to the wheels of said vehicles.

I accomplish my purpose by the mechanism illustrated in the accompanying drawings, in 25 which—

Figure 1 is a transverse section of the pump, showing the frame, the cylinder, the duplicate pistons and their rods, cross-arms, and cam-rollers, the suction and discharge valves 30 and their pipes, partly broken away, and their springs, the water-jacket being omitted. Fig. 2 is a side view of the pump with one of its cam-plates removed, the rim carrying a belt, the inside of the other cam-plate showing its 35 groove, the cylinder broken away at one end, the pistons therein, a piston-rod, two of the cam-rollers, and one of the slots for guiding the cross-arms. Fig. 3 is an end view of the pump with sufficient cut away to expose the 40 interior of a cam, a cross-arm and rollers in the cam-grooves, the cylinder, and the suction and discharge-pipe projections so connected as to also serve as an axle on which the cam-plates and their rigidly-attached rim 45 revolve; and Fig. 4 is a side view of one of the pistons, with a portion broken away, and its piston-ring, the piston-rod and cross-arms, and the two cam-rollers. Fig. 5 is a section 50 of the cylinder and its water-jacket, pistons, and valves.

Similar letters refer to similar parts throughout the several views.

My rotary pump is held in position by base A, frame-pieces A' A', and bearings B B.

C C are cam-plates, and D is a rim rigidly 55 attached to and forming connection between the edges of said plates for the use of a belt. These cam-plates revolve on journals E' E', which journals are formed by projections E E of the cylinder. Cam-plates C C are 60 preferably cast solid, with the groove F inside of each, and are set on opposite sides of cylinder H. When desired, said cylinder may be provided with an outer hollow circular space to be used as a water-jacket T, as 65 shown in Fig. 5. This cylinder is provided with duplicate pistons I I and rods J J and cross-arms K K. These rods are adapted to screw into the pistons, thus allowing adjustment of the pistons for suitable clearance. Each arm carries a pair of rollers L L, adapted to run in grooves F F. Slots M M through the casting of cylinder H serve as guides for the cross-arms, thus permitting 70 said arms to carry the rollers in the cam-grooves. Each of these grooves has a tortuous channel that approaches toward and turns from the center of the cylinder in graceful and regular curves by means of intersecting circular arcs in such a way that 75 by the revolving of the cam-plate the pistons have a reciprocatory movement. Projections E E are cast hollow for the admission into and discharge from cylinder H of air, water, or any liquids or gases and for the reception 80 of suction-valve O and its spring and seat and discharge-valve P and its spring and seat. The cam-plates are provided with and operated on suitable bearings Y Y, placed as 85 shown in Fig. 1. The cam-rollers are operated on roller-bearings Z Z, as shown by dotted lines in Fig. 4.

When the pump as shown and described has been set in motion, it will be readily seen that the cam-plates are at once revolved 95 on their axles. The cylinder H being stationary, these revolutions of the cam-plates and their peculiarly-formed grooves, which do not allow for any dead-center and in which the cam-plates' rollers travel, neces- 100

sarily force the pistons back and forth to their center, the valves and their springs affording means for the ingress and egress of the liquid, air or gas through the suction 5 and discharge pipes.

What I claim, and desire to secure by Letters Patent, is—

1. In a reciprocating power-pump having a rotary operating mechanism the combination 10 with a supporting-frame and the necessary driving power, of duplicate cam-plates and their connecting-rim whose periphery is the driving-pulley, a single stationary cylinder between said cam-plates provided with duplicate 15 slots set longitudinally in the cylinder opposite each other at each end, the duplicate pistons, their rods and the duplicate cross-arms adapted to operate in said slots, the rollers carried at each end of the cross- 20 arms and the duplicate camways in which said rollers are adapted to move or run said camways consisting of a series of concave and convex arcs the four concave arcs of each camway being approximately a one-fourth 25 turn and the four convex arcs a one-eighth turn, and adapted to carry the rollers of said cross-arms so that the rotating motion of the cam-plates will cause reciprocating motion of the pistons at a very high rate of speed 30 without damage to the machine or pump and adapting the pump to service where a high pressure is in a short time required, the suction and discharge pipes projecting oppositely from the cylinder and at right angles 35 to the cylinder and the cam plates and ways, said suction and discharge pipes serving also

as axles for the cam-plates, the suction and discharge valves serving as an inlet and outlet, respectively, for air, liquid or gas, and the valve-springs and valve-seats, substantially as shown and for the purpose specified. 40

2. In a reciprocating power-pump having a rotary operating mechanism the combination with a supporting-frame and the necessary driving power, of duplicate cam-plates provided with a connecting-rim, the duplicate camways consisting of a series of concave and convex arcs the four concave arcs of each camway being approximately a one-fourth 45 turn and the four convex arcs a one-eighth turn, a single stationary cylinder between said cam-plates, the duplicate slots set longitudinally opposite each other at each end thereof, the duplicate pistons adapted to take up all clearance, and their rods, the duplicate cross-arms adapted to operate in said slots and the rollers carried on each end of the cross-arms adapted to run in said camways, the suction and discharge pipes projecting oppositely from said cylinder and at 50 right angles with said cylinder and the cam plates and ways and serving also as axles for said plates, the suction and discharge valves and valve springs and seats, substantially as described and shown. 55

In testimony whereof I affix my signature in presence of two witnesses.

GEORGE W. JOHNSTON.
